UNITED STATES PATENT OFFICE.

JAMES MALLON, OF NEW ORLEANS, LOUISIANA.

CHAIN CONVEYER.

No. 888,918.

Specification of Letters Patent.

Patented May 26, 1908.

Application filed October 3, 1907. Serial No. 395,787.

To all whom it may concern:

Be it known that I, JAMES MALLON, a citizen of the United States, residing at New Orleans, in the parish of Orleans and State of Louisiana, have invented certain new and useful Improvements in Chain Conveyers; and I do hereby declare the following to be a full, clear, and exact description of the invention, such as will enable others skilled in the art to which it appertains to make and use the same.

My invention relates to a chain conveyer, especially applicable to convey trash and other finely divided material, and the object 15 of my invention is to produce such a conveyer as shall be cheap to construct, certain in action, and simple in operation.

To these ends my invention consists in the construction of the links, and the combination 20 of parts more fully hereinafter disclosed, and finally pointed out in the claims.

Referring to the accompanying drawing forming a part of this specification;—Figure 1 represents a side elevation of a portion of 25 my conveyer with the slats in place. Fig. 2 is a plan view of the same with the slats removed, and Fig. 3 is an end view of my conveyer with the slats broken away.

Like letters refer to like parts in all the 30 views.

A represents the slats of my conveyer, which may be of any suitable material, but are preferably made of wood.

B represent the links of my conveyer 35 which are provided with the extended flanges C, the flat faces D, the holes E passing through said flanges, the pivots F, and the rollers G, as shown. The flanges C are furthermore provided with the abutting faces 40 H which extend through the vertical walls J of the links to the rollers G, as shown. These vertical faces H are provided on each end of the said flanges C and vertical walls J, and serve to prevent the slats A from coming 45 together when the conveyer chain is depressed. In addition to this the vertical walls J are provided with the shoulders K forming a continuation of the vertical faces H, as shown.

The vertical walls J are rounded at each 50 end to form the semi-circular portions L, as shown, and the said portions L at the one end of a link overlap or fit into the semi-circular portions L at the other end of an adjacent link, as best shown in Fig. 2. Between the 55 overlapping portions L of two adjacent links

the rollers G are placed and are secured in place by the pins F, above mentioned. The flat faces D being substantially co-extensive with the faces of the slats contacting therewith, and the vertical faces H and the shoulders K preventing the said slats from coming together on their vertical edges, it results that the said slats A are firmly supported, are capable of carrying heavy loads, 65 and that they are amply protected against crushing strains due to a bowing of the conveyer chain when loaded down. That is to say, when the chain is loaded, the supporting rollers G run on any suitable track M, which 70 serves to lessen the friction and to keep the chain in line with the load; but when the chain passes from this track M to the driving sprocket, not shown, the faces H and shoulders K, keep the chain from sagging enough 75 to mash the edges of the slats, A. In addition to this, when the empty portion of the chain is returning on the under side, it has to drop a little out of line to take up the slack. The shoulders K and faces H, while preventing 80 the slats from being mashed, as above described, are so formed that they do not prevent sufficient sagging to keep the chain tight.

The extensive flat faces D serve to amply 85 support the slats A, while at the same time the structure is such that the said slats may be placed so close together that no trash or other small particles may pass between them.

I am aware that conveyer chains provided with rollers and substantially close fitting slats have been heretofore proposed, but I believe myself to be the first to provide links of such a character, which while permitting the slats to be close fitting will yet themselves take from said slats all the lateral crushing strains, when unsupported, and thereby prevent said slats from being crushed by edgewise strains.

What I claim is:—

1. In a chain conveyer the combination of a slat A and a link B, provided with flanges C, and vertical walls J, the said flanges having the vertical faces H at each end, and the said vertical walls J having the shoulders K, 90 at each end, and the said flanges and vertical walls, also, having the flat surfaces D co-extensive therewith and adapted to receive the said slats, substantially as described.

2. In a chain conveyer, the combination of 95 slats A and links B, each provided with vertical walls J, spaced apart and having the

abutting shoulders K, and flanges C, extending beyond said walls and having the abutting faces H extending the full width of said flanges and vertical walls, said vertical walls 5 and flanges also having the flat surfaces D co-extensive therewith adapted to receive said slats, and said vertical walls having the extensions L, substantially as described.

3. In a chain conveyer, the combination of 10 slats A and links B, the said links having the vertical walls J spaced apart and provided with the semi-circular extensions L and the abutting shoulders K at each end, the flanges C extending over said vertical walls at each 15 side of each link and having the abutting faces H, and the rollers G between said extensions L, substantially as described.

4. In a chain conveyer, the combination of 20 a plurality of close fitting slats A, and a plurality of links B each provided with a pair of vertical walls J spaced apart and provided at each end with extensions L, the said extensions on one end of a link adapted to telescope or fit into the extensions on the other

end of an adjacent link, and said walls being 25 each also provided at each end with the abutting shoulders K, flanges C provided with the holes E, extending on each side of each link beyond said walls J, and provided at each end with the abutting faces H, and 30 also provided with the flat surfaces D adapted to receive, and co-extensive with, the engaging surfaces of said slats, rollers G between said telescoping extensions L, and pins F to secure said rollers in place, whereby 35 the said slats may be placed so close together as to prevent trash or small substances from falling between the same, while at the same time all lateral crushing strains due to the load on the conveyer will be received by said faces H and shoulders K, substantially as described.

In testimony whereof, I affix my signature, in presence of two witnesses.

JAMES MALLON.
